UNITED STATES PATENT OFFICE.

THOMAS L. WILLSON, OF BROOKLYN, NEW YORK.

ELECTRIC LOCOMOTIVE.

SPECIFICATION forming part of Letters Patent No. 469,799, dated March 1, 1892.

Application filed July 3, 1891. Serial No. 398,382. (No model.)

To all whom it may concern:

Be it known that I, THOMAS L. WILLSON, a citizen of the United States, residing in Brooklyn, in the county of Kings and State of New York, have invented certain new and useful Improvements in Electric Locomotives, of which the following is a specification.

This invention relates to locomotives for electric railways, designed to simplify the construction thereof, to increase their traction, and in general to render feasible the construction of electric locomotives for pulling heavy trains or for work on steep grades. The invention is also applicable to electric street-cars.

According to my invention I construct a powerful and heavy electromotor and provide friction-wheels fixed on the opposite ends of its armature-shaft and resting in frictional contact with the driving-wheels of the locomotive. The frame of the motor hangs from its armature-shaft, which shaft, being supported by its friction-wheels resting on the locomotive-drivers, transmits the weight of the electromotor to the drivers, thereby maintaining frictional contact or tractive adhesion between the friction-wheels and the drivers and also between the latter and the rails. By preference two pairs of driving-wheels are used in connection with one motor, the pairs being placed close together with the friction-wheel of the motor resting in contact with the two adjacent driving-wheels, so that it simultaneously drives both. The motor is consequently, as it were, hung or suspended at or slightly above its center of gravity from its own axis by reason of the position of its friction-wheels in the gaps between the successive pairs of drivers. The drivers are connected together by a suitable frame-work, which may be made integral or connected to the frame of the motor. The motor is so connected to the driving-wheels or to the frame connecting them or to any other suitable frame-work of the locomotive as to prevent its displacement around its axis by reason of the thrust transmitted to it through the driving-wheels.

Figure 1 of the accompanying drawings is a side elevation of my improved electric locomotive, except that the driving-wheels are removed and their axles and the casing or cab of the locomotive are shown in vertical

section. Fig. 2 is a side elevation of the driving-wheels and the friction-wheel gearing with them. Fig. 3 is an end elevation of the locomotive, its cab being in vertical section. Fig. 4 is a vertical section of the electromotor on the line 4 4 in Fig. 1. Fig. 5 is a fragmentary section of the locomotive, and Fig. 6 is a fragmentary section showing a modification.

Referring to the drawings, let A A indicate the driving-wheels of the locomotive, B B their axles, C any suitable frame connecting them which may constitute a part of the electromotor, and M the electromotor as a whole. 55 This motor M is constructed with a field-magnet D and an armature E, fixed on an armature-shaft F, on the opposite ends of which are two friction-wheels G G, which rest against flanges A² on the driving-wheels A A on opposite sides.

The particular construction of electromotor shown is in general similar to the construction of dynamo shown in my patent, No. 406,015, dated June 25, 1889. It particularly 65 resembles the dynamo in that patent in having its armature constructed to constitute in itself a commutator, the commutator-brushes H H being arranged to bear against the periphery of the armature. To this end the armature is constructed with an annular core 70 covered with a "winding" of segmental copper bars forming a continuous spiral conductor around the core and insulated from it and from each other. The segmental bars 75 on the exterior of the commutator are uninsulated and are turned down cylindrically to form a commutating-surface, to which the commutator-brushes H H are lightly pressed. These brushes may be very wide and ex- 80 tended nearly the entire length of the armature. This construction of armature-commutator is especially well adapted to an electromotor designed for heavy work, as no space is required at either end of the armature for 85 the insertion of a commutator, as in other motors, and the field-magnet may consequently be brought close against the ends of the armature, thereby making the motor very compact and consequently enabling a larger, heavier, and more powerful motor to be mounted in a given space. The space in which a motor can be mounted on an electric locomotive 90 is apt to be limited or determined largely by

the gage of the track on which the locomotive is to run.

In the construction shown the field-magnet D consists of a rectangular frame, from the 5 ends of which cores project inwardly, wound with wire to form the field-magnet coils a a, and carrying pole-pieces b b, partially embracing the armature above and below. The shaft F passes through the rectangular frame 10 of the field-magnet at the middle thereof, and the magnet-frame is there formed with bearings c c for this shaft. The entire weight of 15 the field-magnet is hung from these bearings and transmitted through the shaft to its friction-wheels G G and through them to the driving-wheels A A. As the armature is caused to revolve its rotation is transmitted through the shaft F to the friction-wheels G G and from them to the driving-wheels A A. 20 By reason of the entire weight of the motor being transmitted through the friction-wheels to the driving-wheels a strong frictional contact is produced, so that the thrust of the friction-wheels is made effective to drive the driving-wheels and consequently to propel the locomotive. This effect is increased by the 25 arrangement of the friction-wheel G partially between the two adjacent pairs of driving-wheels, so that its thrust is transmitted angularly to each and equally distributed between them. The angular thrust of the friction-wheels G G tends to press the pairs of driving-wheels apart, and to resist this tendency their axles are mounted to turn in boxes d, 30 which are mounted in straps or hangers e of any suitable construction adapted to permit up-and-down movement of the boxes, but to resist their movement toward or from each other in longitudinal direction, so that the 35 axes of the driving-wheels are kept at the proper distance apart. The hangers e e are connected through the frame C, before mentioned, which frame in the construction shown consists of the lower portion of the field-magnet frame; but this is not essential, 40 as a separate frame might be used for this purpose. By using the field-magnet frame, however, the construction is simplified, since the same frame serves not only the functions 45 of a field-magnet, but also serves to hold the axle-boxes at the proper distance apart and to maintain the upright position of the electromotor, thereby resisting any angular reaction due to the thrust exerted by the motor 50 against the driving-wheels. Various other means of mounting may, however, be applied to accomplish this purpose, as will be readily apparent to any constructive mechanic.

It is an important advantage of my invention 55 that by the peculiar mounting of the electromotor its weight is not only utilized to impart traction to the driving-wheels, but the motor tends constantly to maintain a position where this traction will be equally distributed 60 between the wheels. In case, for example, in running over an irregular track either pair of wheels should move up or down, the weight

of the motor is so disposed as to keep the friction-wheels G G in continual contact with the driving-wheels, notwithstanding any variations in their movement. 70

The commutator-brushes may be variously arranged. I have shown two pairs of such brushes, those lettered H H being arranged to make contact with the armature in running forward and those lettered H' H' being used in backing. For governing the speed any means may be provided that are known in the art. 75

In the drawings I have shown the car-body or cab J mounted on the frames C C, which is a convenient construction, especially for a motor having only two pairs of driving-wheels, as shown. For locomotives for heavier work three, four, or more pairs of 80 wheels may be used, and they may be mounted and arranged according to any of the various ways employed for mounting locomotive-wheels or car-wheels. In any case where it is desired that the car-body, floor, or cab shall 85 be mounted independently of the motor it may be connected to the wheels in any manner now known for connecting locomotive-bodies or car-bodies to their wheels. The motor may be connected to such framing or car-body in any suitable manner by which the motor shall be left free to move up or down to accommodate itself to the movements of the driving-wheels, but shall be restrained only against angular displacement due to the 90 reaction from the thrust it communicates to the drivers. The structural changes thus suggested are all within the mechanical judgment or discretion of the constructive engineer and may be applied without departing 95 from my invention. It is desirable to make the mounting of the motor somewhat elastic. This is preferably accomplished as shown in Figs. 1 to 5. In this construction the driving-wheels A are formed with an outer flange A², 100 which has a metallic tire f and an elastic cushion of rubber or yielding material g interposed between the tire f and the flange A², and the friction-roller G is also provided with a similar metallic tire h and an elastic cushion i between the tire h and the body of the wheel. These yielding cushions within the tires constitute an elastic medium for reducing the 105 shocks or vibration of the driving-wheels and thereby easing the motion of the motor M. This construction is especially desirable for rough roads or high speeds. In lieu of elastic cushions, yielding wheels may be employed in place of the driving-wheels A and friction-wheels G. As such wheels are well 110 known in the art, I do not deem it necessary to 115 illustrate them.

Fig. 6 shows a simple form of my invention, in which the wheels G G bear directly on the threads of the driving-wheels A A. 120

It will be understood that the ends of the motor-shaft F may themselves constitute the wheels G G where it is desired to use a motor of high armature-speed. 125

I claim as my invention the following-defined novel features, substantially as hereinbefore specified, namely:

1. In an electric locomotive, the combination of two pairs of driving-wheels arranged close together and an electromotor having opposite friction-wheels on its shaft, said wheels entering partially between and resting on friction wheels or surfaces on the respective advancing and following driving-wheel axles, the motor constructed and mounted so that its weight is hung from its shaft, so that it serves to press the friction-wheels into tractive contact, and the frame of the motor constructed to engage the bearing-boxes of the driving-axles to maintain them at the proper distance apart and to resist the reactive thrust of the motor.

2. In an electric locomotive, the combination of two pairs of driving-wheels arranged close together, an electromotor having opposite friction-wheels on its shaft, said wheels entering partially between and resting on friction wheels or surfaces on the respective advancing and following driving-wheel axles, and the field-magnet of the motor formed with bearings for said shaft and supported by being hung from said shaft through its bearings, whereby the weight of the field-magnet is utilized to press the respective friction-wheels into tractive contact.

3. In an electric locomotive, the combination of two pairs of driving-wheels arranged close together, an electromotor having opposite friction-wheels on its shaft, said wheels entering partially between and resting on friction wheels or surfaces on the respective advancing and following driving-wheel axles, and the field-magnet of the motor formed with bearings for said shaft and supported by being hung from said shaft through its bearings, whereby the weight of the field-magnet is utilized to press the respective friction-wheels into tractive contact, and one of the friction-wheels on each side constructed with a yield-

ing cushion, whereby the weight of the motor is elastically upheld.

4. In an electric locomotive, the combination of two pairs of driving-wheels arranged close together, an electromotor having opposite friction-wheels on its shaft, said wheels entering partially between and resting on friction wheels or surfaces on the respective advancing and following driving-wheel axles, the field-magnet of the motor arranged vertically with its pole-pieces above and below the armature, formed with bearings for said shaft, and supported by being hung from said shaft through its bearings, whereby the weight of the field-magnet is utilized to press the respective friction-wheels into tractive contact, and the armature constructed with bared external surfaces on its conducting, winding, and commutator brushes bearing on said external surfaces in the gaps between the pole-pieces.

5. In an electric locomotive, the combination of two pairs of driving-wheels arranged close together, an electromotor having opposite friction-wheels on its shaft, said wheels entering partially between and resting on friction wheels or surfaces on the respective advancing and following driving-wheel axles, and the field-magnet of the motor formed with bearings for said shaft and supported by being hung from said shaft through its bearings and having supporting-frames attached to it, and the car-body mounted on and supported by said frames, whereby the weight of the car-body is added to that of the field-magnet and their combined weight is utilized to press the respective friction-wheels into tractive contact.

In witness whereof I have hereunto signed my name in the presence of two subscribing witnesses.
